UNITED STATES PATENT OFFICE.

THOMAS C. KENNEDY, OF BALTIMORE, MARYLAND

BAIT-BUCKET.

1,054,561.

Specification of Letters Patent. Patented Feb. 25, 1913.

Application filed September 18, 1912. Serial No. 720,924.

To all whom it may concern:

Be it known that I, THOMAS C. KENNEDY, a subject of Great Britain, and resident of Baltimore, Maryland, have invented certain 5 Improvements in Bait-Buckets, of which the following is a specification.

This invention in common with others of its class, relates to a bucket for holding live minnows, used by fishermen as bait, and 10 which is collapsible so as to occupy little space during transportation, or when not in use.

The said invention consists principally, in a folding casing which is pervious to 15 water, preferably provided with an air chamber whereby the device will float, combined with a flexible bag, situated within the casing, so constructed as to lie in a collapsed condition on the bottom of the casing, 20 or to be drawn up to produce with the casing a water-tight bucket.

The said invention consists further in means whereby the flexible bag can be collapsed, or extended, at pleasure, and in various 25 other details of construction of the bucket, as will hereinafter fully appear.

In the further description of the said invention which follows, reference is made to the accompanying drawings forming a part 30 hereof, and in which:—

Figure 1 is a perspective view of the improved bucket as it appears when adapted to hold water; and Fig. 2 a perspective view of the same when collapsed. Fig. 3 is a vertical 35 section of the bucket showing the flexible lining or bag as collapsed at its bottom; and Fig. 4 a perspective view of the casing when extended. Fig. 5 is an enlarged section of a part of the flexible lining or bag.

40 Referring now to the drawings, 1 is the rectangular bottom of the casing of the bucket, formed preferably of sheet aluminum on account of its levity.

45 2, 2 are the sides of the casing, also of aluminum, hinged to the bottom 1 in such manner as to admit of their being erected to produce a receptacle which is closed at the top by the flanged lid 3 having a hinged door 4 therein.

50 To retain the lid in place, spring catches 5 are riveted to the sides 2, and pass through slots 7 in the lid.

In order that the bucket may float when placed overboard, there is applied to the 55 underside of the lid an inflatable tube 9 of

say rubber, having an ordinary valved nozzle 10, when the tube is exhausted of air it collapses and does not interfere with the folding of the sides 2 over the bottom of the casing, or the application of the lid thereto 60 as shown in Fig. 2.

If desired, the side 2 of the casing may be perforated to admit of the passage therethrough of a current of water when the bucket is in a swiftly running stream, but 65 to prevent the forcing of the live minnows against the down stream side of the bucket which would tend to injure them, I prefer to perforate that side only, or better still, insert in the said side, a gauze panel 12 70 shown in Figs. 1 and 4; and to preserve this position of the bucket with respect to passing water, when the bucket is tied to a boat, and also to keep the bucket in as near a vertical position as is possible, I provide the 75 adjoining sides of the casing with rings 13 to which the two ends of a holding cord is attached.

15 is the water-tight bag or lining for the casing, before referred to. At its bottom it is 80 provided with a rectangular wire frame 17, and several similar frames 20 are attached to its sides at proper distances apart. These frames not only serve to retain the bag in a normally collapsed condition, but also tend 85 to keep its sides in practically straight vertical lines when the bag is extended or drawn up.

To admit of the ready extension of the bag 15, I attach to two opposite sides of the 90 upper wire frame, by means of rings 21 or some other loose hinging devices, the bails 22 the side section of which, when the bag is collapsed, pass through slots 24 in the lid 3 as shown in Fig. 3.

When the bag is drawn up, the bails form a convenient handle for carrying the bucket, as shown in Fig. 1; and when the device is collapsed as represented in Fig. 2, the bails 100 fold one upon another on the lid, the ring hinges 21 projecting through the slots 24.

After the bag is drawn up by means of the bails, and the bails released, they naturally fold upon the lid by gravity, and thus automatically sustain the bag in its elevated 105 position.

To prevent accidental tampering with the bails in such manner as to cause them to drop the bag to the bottom of the casing, I provide the upper surface of the lid with 110

catches adapted to engage the hinge rings 21. One only of these catches is shown in Fig. 1 in dotted lines and denoted by 26.

As it is not desirable that the bag should 5 ever be entirely filled with water, I provide at least one of its sides near the upper edge, with overflow holes 27. These are illustrated in Figs. 1 and 5 of the drawings.

I claim as my invention:—

- 10 1. In a bucket for the purpose described, a pervious casing, combined with an impervious or water-tight collapsible bag situated within the casing, and means whereby the collapsible bag can be extended and secured in that condition, substantially as specified.
- 20 2. In a bucket for the purpose described, a casing composed of a bottom, sides hinged to and adapted to fold over the bottom, and a lid, combined with a water-tight collapsible bag situated within the casing and means whereby the said bag can be collapsed, or extended, from the exterior of the device, substantially as specified.
- 25 3. In a bucket for the purpose described, a casing composed of a bottom, sides hinged to and adapted to fold over the bottom, and a lid carrying on its underside an inflatable tube, combined with a water-tight col-

lapsible bag provided with stiffening frames, 30 situated within the casing, and bails hinged to the said bag and adapted to slide vertically through slots in the lid, and to fold over the same so as to hold the bag in an extended condition, substantially as specified. 35

4. In a bucket for the purpose described, a casing composed of a bottom, sides hinged to and adapted to fold over the bottom, and a lid carrying on its underside an inflatable tube, combined with a water-tight collapsible bag, situated within the casing, substantially as specified. 40

5. In a bucket for the purpose described, a casing composed of a bottom, sides hinged to and adapted to fold over the bottom, and a lid carrying on its underside an inflatable tube, combined with a water-tight collapsible bag, situated within the casing, and bails hinged to the said bag and adapted to slide vertically through slots in the lid, and to fold over the same so as to hold the bag in an extended condition, substantially as specified. 45 50

THOS. C. KENNEDY.
